ANTIREFILL DEVICE

Henry A. Fisher, Parkersburg, W. Va.

Application February 6, 1942, Serial No. 429,809

15 Claims. (Cl. 215—25)

This invention relates to anti-refill devices or units for necked containers such as bottles.

Many forms of such devices have been proposed heretofore but have been objectionable for various reasons. For one thing, where at all effective, they have been of complicated construction and expensive, and for another thing, and principally, they have usually required a special container construction to provide for anchoring, or it has been necessary to secure the devices in the containers by cementing. An object of the present invention is to overcome these objections by providing such devices as may be readily and cheaply made from plastics, and which are so designed as to be effectively retained in the necks of standard containers without any modification whatever of the latter and without the use of any extraneous means, such as cement.

In illustration of how the invention may be carried out, practical embodiments are shown in the accompanying drawings with reference to which the description will proceed.

In these drawings:

Figure 1 shows in elevation an anti-refill device, in accordance with the invention, operatively disposed in a bottle neck, the latter being shown in axial section.

Figure 2 is a plan view of the non-refill device of Figure 1.

Figure 3 is a section on line 3—3 of Figure 2.

Figure 4 is a section on line 4—4 of Figure 3.

Figure 5 is a section on line 5—5 of Figure 3.

Figure 6 is a section on line 6—6 of Figure 3.

Figure 7 is a section on line 7—7 of Figure 2.

Figure 8 is an axial section of an auxiliary guard associated with the anti-refill device.

Figure 9 is a bottom plan view of the guard of Figure 8.

Figure 10 is an elevation of the anti-refill device including the auxiliary guard of Figures 8 and 9.

Figure 11 shows in elevation another form of anti-refill device in accordance with the invention, the device being shown in operative association with a bottle neck which appears in axial section.

Figure 12 is a view like that of Figure 11, but showing the parts in pouring disposition.

Figure 13 is a plan view of the non-refill device of Figures 11 and 12.

Figure 14 is a section on line 14—14 of Figure 13.

Figure 15 is a section on line 15—15 of Figure 14.

Figure 16 is a section on line 16—16 of Figure 14.

Figure 17 is an elevation of a further form of device in accordance with the invention.

Figure 18 is a plan view of the device of Figure 17.

Figure 19 shows in elevation the device of Figures 17 and 18 in operative association with a bottle neck which appears in axial section.

Figure 20 is a section on line 20—20 of Figure 18.

Figure 21 is a section on line 21—21 of Figure 20.

Figure 22 is a section on line 22—22 of Figure 20, and

Figure 23 is a section on line 23—23 of Figure 20.

Referring first to Figures 1 to 10, the anti-refill device or unit generally indicated by the reference numeral 25 includes a top or outer portion 26 in the form of an annular fin which is inwardly dished at 27 to a circular pouring opening 28, the lower wall of the fin being upwardly curved to meet the top wall at a thin edge 29. As appears most clearly in Figures 3 and 7, the radial section of the fin is substantially that of the marginal portion of a relatively flat converging meniscus. Integral with the fin 26 are three downwardly extending legs 30 whose outer edges are spaced inwardly from the edge 29 to leave a free lip portion and below the opening 28 these legs have integrally formed therewith a ring 31 and a disc or table 32, the diameter of the ring 31 being preferably somewhat greater than that of the opening 28 and the diameter of its opening 33 being preferably somewhat less than the diameter of disc 32, the ring and disc being coaxial and somewhat spaced apart. Below the disc 32 the inner portions of the legs are reduced to the relatively fragile triangular section shown in Figure 3 and their extremities are set into and cemented in mating recesses formed in the top wall of a bottom or inner fin 34 whose section is like that of the top fin as particularly seen in Figures 3 and 7. The legs 30 and fin 34 constitute a cage for a ball 35 which is cooperable with a mating seat 36 which rims the opening of fin 34, ball 35 being preferably constituted by a marble. The entire frame of the unit is molded from a plastic such as polystyrene and as here shown preferably comprises only two parts which are welded or cemented together by the use of a solvent such as ethyl acetate.

The bottle neck 37 has a smooth substantially

cylindrical inner wall 38 and in ordinary manufacture the neck opening is of substantially true circularity at least for some distance inwardly from the bottle lip. Fin 26 has an overall diameter somewhat greater than the neck diameter and the overall diameter of fin 34 is ordinarily slightly less than that of fin 26. In associating the device with the bottle neck, a suitable pushing tool is applied to the face 27 and the device is pushed into the neck to the position, or thereabouts, shown in Figure 1. While the lip of fin 26 is circumferentially contractible, by being forced into a more extremely cupped condition than normal, it is resistant to contraction and exerts a powerful expanding action against the inner wall of the neck and not only seals the neck off in to the opening 28, but also serves to retain the device in the neck against removal. Fin 34 seals off the neck in to the seat 36 and consequently it is only through the latter that the container contents can reach the pouring opening 28. Fin 34 also has an anchoring and centering effect. The diameter of the bottom fin is, as above stated, preferably somewhat smaller than that of the top fin in order that in the inserting process the legs 30 will not be subjected to such compression as would bend or break them. It is desirable, however, that the frictional engagement of the bottom fin be as great as is safely possible.

If, for example, a pressure of sixty pounds has been necessary to insert the device in the bottle neck, it will be seen that, due to the wedging effect, a considerably greater force will be required to extract it and since this force can only be applied at points around the opening 28, the fin will almost certainly be broken if an attempt is made to remove it. Furthermore, even if the top fin can be pulled outwardly without breakage, the legs 30 are apt to be subjected to breaking tension due to the resistance of the fin 34. It is thus impossible to remove the device without destroying it. The frictional resistance of the fins is determined by the resiliency of the material, over-all diameter in relation to the inner diameter of the neck, and thickness.

It will be evident that in the normal disposition of the device as shown in Figure 1, refilling of the bottle is made impossible by the seating of ball 35 and that due to the provision of the baffle means constituted by ring 31 and disc 32 it is hardly possible to reach the ball with a retracting instrument.

The guard 39 shown in Figures 8 to 10 constitutes an additional precaution which may be used if desired. This guard, as here shown, includes a disc portion 40 of the same diameter as the opening 28, and depending from the disc are three legs 41 provided with angular bottom notches 42. Ring 31 is provided on its top face with three angular protuberances 43 which are spaced apart as the legs 41. In assembly the legs 41 are inserted through the opening 28 and protuberances 43 are engaged in notches 42 and cemented, the length of the legs being such that the disc portion 40 will be spaced above the top of opening 28. If it should be attempted to remove the thus equipped device from a bottle neck, traction on the disc 40 will merely result in breaking the legs 41 or the joint at their lower ends. The presence of the guard makes it practically impossible to engage any effective extracting tool under the fin 26.

Figures 11 to 16 illustrate a dual valve unit in

accordance with the invention. Referring to these figures, the anti-refill device is indicated as a whole by the reference numeral 45. It comprises a top or outer disc 46 whose marginal portion 47 constitutes a fin shaped like those previously described. The disc has a central perforation 48 and three arcuate slots 49 concentrically disposed relative to the perforation. Three integral legs 50 depend from disc 46 and have their lower ends cemented to a bottom or inner disc 51 which includes a fin portion 52. Disc 51 is provided with a central opening 53 whose margins provide a seat for a ball 54 which is movable in the cage defined by legs 50 and disc 51. 15 A cage 55 in the form of a cup has the free edge of its imperforate side walls set into and cemented in an annular groove in the bottom of disc 51. The bottom wall of cage 55 is provided with a central opening 56 whose margins provide 20 a seat for a second ball 57 which, as here shown is somewhat smaller than the ball 54 yet larger than the lower end of opening 53. Also, as here shown, the bottom wall of cage 55 is continued outwardly into a peripheral fin 58 which is shaped 25 as the other fins.

In Figure 11 the unit 45 is shown operatively positioned in a bottle neck 59. As in the first embodiment, the top fin provides the main frictional engagement, fins 52 and 58 being of some- 30 what smaller diameter so that not too much compressive strain will be imposed on the parts between the fins during insertion. Since the cage 55 is imperforate, fin 58 may be omitted or, on the other hand, with fin 58 present the side walls 35 of the cage 55 may be perforate. In the illus- trated construction, however, fin 58 prevents the loss of the small quantity of liquid which might otherwise enter the space 59'. When the bottle 40 is tilted for pouring as in Figure 12, both balls leave their seats and ball 57 is prevented, in any normal pouring position, from seating against the lower margins of opening 53 by reason of the fact that the radius of the ball is less than the radial distance from the inner surface of the 45 side walls of cage 55 to the lower edge of opening 53, as seen in Figure 12. Disc 51 thus pro- 50 vides a retaining ledge for the ball. If it were to be attempted to refill the bottle, ball 54 can be reached to some extent through the openings 48 and 49 of disc 46, but ball 57 is completely inaccessible. In any attempted vacuum refilling operation ball 57 would be dislodged from the position shown in Figure 12 and seat against the lower edge of opening 53 to block the latter.

55 Referring now to Figures 17 to 23, the anti- refill unit designated as a whole by the reference numeral 60 comprises an upper portion 61 which is more extremely dished than the fin portions heretofore described and may be said to be generally bell-shaped. As here shown, this upper portion is provided with minute radial slits 62 which extend throughout the upper portion to the lower cage portion 63 which is integral therewith and has solid walls. Portion 63, as here shown, has four internal longitudinally extending ribs 64 which extend upwardly to plane 65 where the outer portion 61 begins. A wheel-like member 65 has a rim 66 cemented on top of ribs 64 and 66 spokes 67 which meet at a central hub 68. A pin 69 rises from the hub 68 and the extremity of the pin is reduced and is engaged and cemented in a central opening of a disc 70 which bears against the underlying shoulder. Three 70 legs 71 which project upwardly from disc 70 sup-

port a ring 72 which has a central opening smaller than disc 70, the outer edge of ring 72 being spaced somewhat inwardly from the inner walls of the outer portion 61. Cage portion 63 has a central bottom opening 63' whose margins constitute a seat for a ball 73.

The unit 60 is inserted in the bottle neck 74 by engaging a suitable tool with the edge of portion 61. Due to the flare of the latter and the provision of the slits 62, its lip is evenly contracted to afford a band 75 of contact with the inner walls of the bottle neck and due to this axial zone of contact the unit is maintained in coaxial relation with the neck. The slits 62 are substantially closed and in any event are too minute to pass any substantial amount of liquid either into or out of the container. Since the cage 63 is imperforate except for the opening 63', it is only through the latter that the container contents have access to the pouring opening of the unit. It will be seen that the baffle provisions 70 and 72 render impossible any access to ball 73 from the outer end of the unit and any extractive pull on them will result in breakage since they are unable to withstand sufficient traction to overcome the frictional engagement of the unit in the bottle neck.

In all cases the anti-refill device or unit, with the exception of the ball or balls, is preferably made entirely of molded plastic, and injection molding is desirably used in making all parts capable of production in that manner. While polystyrene has been mentioned as a suitable plastic, other suitable synthetic materials of semi-flexible composition may be used. The invention is by no means limited to the specific details which have been disclosed by way of example, variations in the form and arrangement of parts being contemplated under the claims which follow. In these claims, directional terms such as outer, inner, etc., are used merely as a matter of convenient description and without limiting intent.

I claim:

1. An anti-refill device insertable in a smooth-walled container neck for retention therein, said device being of molded plastic and comprising an inwardly dished outer portion defining a pouring opening and including an annular lip beveled to a thin circumferential outer edge, said lip being circumferentially contractible but so resistant to contraction and of such diameter as to tightly engage the container neck against removal when inserted therein, a cage fixed to said outer portion inwardly of the latter and including a seat defining an opening affording the only means of access of the container contents to said pouring opening when the device is in the container neck, and a movable valve body in said cage cooperable with said seat, said device including baffle means barring access to said valve body from the outer end of the device.

2. A device according to claim 1 wherein said baffle means includes a solid disc and a ring which are spaced apart and coaxially arranged, said ring having an outer periphery at least substantially as great as the inner periphery of said pouring passage and an opening whose size is at most not substantially greater than the size of said disc.

3. A device according to claim 1 wherein the cage has lateral openings and has a peripheral fin adapted to form a seal with the bottle neck to prevent by-passing of the seat opening by the container contents.

4. A device according to claim 1 wherein the cage has solid walls preventing by-passing of the seat opening by the container contents.

5. A device according to claim 1 wherein the lip is solid and its radial section is substantially that of the marginal portion of a relatively flat converging meniscus.

6. A device according to claim 1 wherein said outer portion is substantially bell-shaped, is provided with fine radial slits, and contracts upon insertion in the container neck to provide a band of contact with the container neck.

7. An anti-refill device insertable in a smooth-walled container neck for retention therein, said device being of molded plastic and including top and bottom annular fins of which the top fin is dished inwardly and has a radial section substantially that of the marginal portion of a relatively flat converging meniscus, axially extending legs joining said fins, a ball retained between said fins by said legs, the inner margins of the bottom fin opening constituting a seat for said ball, and baffle means supported by said legs barring access to said ball through the opening 25 of the top fin, the top fin being circumferentially contractible but so resistant to contraction and of such diameter as to tightly engage the container neck against removal when inserted therein and the bottom fin being adapted to seal 30 off the container neck in said seat.

8. A device according to claim 7 wherein the radial section of the bottom fin is like that of the top fin and its diameter is slightly less than that of the top fin.

9. A device according to claim 7 wherein said baffle means includes a solid disc and a ring which are spaced apart and coaxially arranged, said ring having an outer periphery at least substantially as great as the inner periphery of the top fin and an opening whose size is at most not substantially greater than the size of said disc.

10. A device according to claim 7 wherein a guard disc is supported in spaced overlying relation to the top fin opening.

11. A device according to claim 7 wherein a cage extends below said bottom fin and includes a bottom opening affording the only means of access of the container contents into said cage when the device is in the container neck, wherein a ball in said cage cooperates with the margins of said bottom opening as a seat, and wherein means are provided preventing the second ball from seating in the opening of said bottom fin when the container is tipped for normal pouring but permitting said second ball to seat in said bottom opening under abnormal conditions.

12. An anti-refill device insertable in a smooth-walled container neck for retention therein, said device being of molded plastic and including top and bottom annular fins and relatively fragile legs joining said fins, and a ball movable between said fins within said legs and adapted to seal the opening of the bottom fin, said fins frictionally engaging the device in a bottle neck when inserted therein, said legs being sufficiently strong to transmit inserting pressure from the top to the bottom fin but apt to separate under tension if extractive force is applied to the top fin.

13. The combination with a container having a neck with smooth inner walls, of an anti-refill device of molded plastic inserted in said neck, said device including an annular fin providing a pouring opening, said fin being inwardly dished and having a free lip portion which is circum-

ferentially contractible but is so resistant to contraction and of such original diameter as to tightly engage the container neck when pushed therein so that said device is retained against removal solely by friction, said fin sealing off the container neck in to said pouring opening.

14. The combination according to claim 13 wherein the radial section of the fin is substantially that of the marginal portion of a relatively flat converging meniscus.

15. The combination with a container having a neck with smooth inner walls, of an anti-refill device of molded plastic inserted in said

5 neck, said device including an annular fin providing a pouring opening, said fin being inwardly dished and having a free lip portion which is circumferentially contractible but is so resistant to contraction and of said original diameter as to tightly engage the container neck when pushed therein so that said device is retained against removal solely by friction, said fin sealing off the container neck in to said pouring opening, 10 said device also including means spaced axially of the neck from said fin and engaging the neck to center said fin therein.

HENRY A. FISHER.
